UNITED STATES PATENT OFFICE.

WILLIAM HOWE RUSSELL, OF WALWORTH, NEBRASKA.

WASH-BOILER.

SPECIFICATION forming part of Letters Patent No. 372,433, dated November 1, 1887.

Application filed May 10, 1887. Serial No. 237,731. (No model.)

To all whom it may concern:

Be it known that I, WILLIAM HOWE RUSSELL, a citizen of the United States of America, residing at Walworth, in the county of Custer and State of Nebraska, have invented certain new and useful Improvements in Washing - Machines, of which the following is a specification, reference being had therein to the accompanying drawings.

10 This invention pertains to certain new and useful improvements in washing - machines; and it consists in the detailed construction, combination, and arrangement of the parts, substantially as hereinafter fully set forth, and particularly pointed out in the claim.

15 In the accompanying drawings, Figure 1 is a plan view of my invention with the lid or cover removed. Fig. 2 is a longitudinal sectional view thereof, and Fig. 3 is a bottom plan view.

20 The object of this invention is to provide means for the ready washing and cleansing of clothes by the application thereto of the boiling-water from different points of the receptacle or steam-chest, and at the same time not to allow the water to attain such height as to cause the clothes to be entirely submerged thereby.

25 In carrying out my invention to accomplish the above objects, I employ a square or oblong boiler, A, wherein I dispose the receptacle or steam-chest a, the sides and ends of which are apertured, as shown.

30 B is a frame or stand secured to the under side of the receptacle or steam chest a, at the lower outer edges thereof, and in the sides of this frame or stand I form corresponding recesses or openings, b b. In these recesses or openings are secured the outer flanged ends of inclined plates, bearing at their inner ends 35 against the bottom of the steam-chest, the same forming part of a skeleton bottom, C. (Shown in Fig. 3.) This bottom comprises a series of

vertically-disposed V-shaped plates, b', forming ducts or passage-ways b'', extending to each of the four corners of the bottom of the 45 steam-chest.

Through the bottom of the steam-chest, at the corners thereof, project four pipes, D, the lower ends of which enter the ducts or passage-ways b'' of the skeleton bottom, while the upper ends are bent at right angles toward the center of the steam-chest. The steam-chest is provided with a suitable tight-fitting cover, d, as shown.

From what has been said it will be seen that 55 when the water contained in the boiler reaches a high boiling temperature the same will be guided by the ducts or passage-ways b'' to and pass through the pipes D and fall onto the clothes contained in the steam chest or receptacle, effecting a thorough cleansing thereof, and, passing off through the apertures in the sides of the steam-chest, returning to the boiler. This operation is continued until the clothes are thoroughly cleansed, which is accomplished 60 in a most effective manner and in a short space of time.

I claim as my invention—

The combination, with the boiler, of the steam chest or receptacle having apertured 70 sides, the frame or stand provided on each side with openings or recesses, the skeleton bottom comprising the ducts or passage-ways connected to said frame or stand at said openings or recesses, and the pipes extending into said 75 steam chest or receptacle, substantially as shown and described.

In testimony whereof I affix my signature in presence of two witnesses.

WILLIAM HOWE RUSSELL.
